UNITED STATES PATENT OFFICE

159,656

WEDDING RING OR SIMILAR ARTICLE

Joan Linden, Los Angeles, Calif.

Application June 20, 1949, Serial No. 3,409

Term of patent 14 years

(Cl. D45—10)

To all whom it may concern:

Be it known that I, Joan Linden, a citizen of the United States, residing at Los Angeles, in the county of Los Angeles, State of California, have invented a new, original, and ornamental Design for Wedding Ring or Similar Article, of which the following is a specification, reference being had to the accompanying drawing, forming a part thereof.

Figure 1 is a side view of a ring showing my new design.

Figure 2 is an edge view thereof.

Figure 3 is a sectional view, enlarged, as on a line 3—3 of Figure 1.

Figure 4 is an enlarged side elevational view of a section of the finger ring as shown in Figure 1.

The dominant feature of my design for a wedding ring or similar article resides in the letters of the character shown disposed around the ring circumference between the steeply sloping flanges, which flanges terminate at the bot-

tom edge of the ring, said letters conforming in curvature to both the transverse and the circumferential curvature of the ring.

I claim:

The ornamental design for a wedding ring or similar article, as shown and described.

JOAN LINDEN.
